WRIST WATCH

Philipp Kurth, Granges, Switzerland, assignor to Certina
Kurth Freres S.A., Granges, Switzerland

Filed Aug. 20, 1970, Ser. No. 24,589

Term of patent 14 years

Int. Cl. D10—02

U.S. Cl. D42—8

FIG. 1

FIG. 2

FIG. 1 is a top perspective view of a wrist watch showing my new design.

FIG. 2 is a bottom plan view thereof.

The characteristic feature of my design resides in the positioning and configuration of the indicia bearing apertures.

I claim:

The ornamental design for a wrist watch, substantially as shown and described.
